UNITED STATES PATENT OFFICE

100,886

DESIGN FOR A GAME BOARD

Albert K. Winans, Toledo, Ohio

Application March 16, 1936, Serial No. 61,651

Term of patent 7 years

To all whom it may concern:

Be it known that I, Albert K. Winans, a citizen of the United States and residing at Toledo, in the county of Lucas and State of Ohio, have invented a new, original, and ornamental Design for a Game Board, of which the following is a specification, reference being had to the accompanying drawing forming a part thereof.

The figure is a plan view of a game board which is of no appreciable thickness and shows my new design.

I claim:

The ornamental design for a game board substantially as shown and described.

Signed at Toledo, in the county of Lucas and State of Ohio, this 10th day of March, 1936.

ALBERT K. WINANS.
